HEADLIGHT TESTER

James G. Collins, Kalamazoo, Mich., assignor to
Atlas Press Company, Kalamazoo, Mich.

Application March 13, 1931, Serial No. 522,281

10 Claims. (Cl. 88—14)

The main object of this invention is to provide an apparatus by means of which the focusing of headlights may be quickly and easily gaged.

A further object is to provide an apparatus of this character which is portable and readily adjusted to vehicles having headlights at various elevations and positions.

Objects pertaining to details and economies of my invention will definitely appear from the 10 description to follow. The invention is defined in the claims.

A structure which embodies the features of my invention is clearly illustrated in the accompanying drawings, in which:

15 Fig. 1 is a perspective view of an apparatus embodying the features of my invention.

Fig. 2 is a fragmentary view mainly in vertical section on line 2—2 of Fig. 1 showing certain details of the adjusting means and also of the 20 finder or reading gage.

Fig. 3 is a fragmentary elevation of the adjustable pedestal or standard.

Fig. 4 is a horizontal section on line 4—4 of Figs. 1 and 5 showing details of the reflector and 25 its housing, the reflector being shown in open position by full lines and in closed position by dotted lines.

Fig. 5 is a fragmentary view mainly in vertical section on a line corresponding to line 5—5 of 30 Figs. 1 and 4.

Fig. 6 is a detail view sectioned on line 6—6 of Fig. 5, showing further details of the reflector housing.

Referring to the drawings, I provide a frame 35 1 provided with a pair of wheels 2 at one end and having a standard or pedestal at its opposite end. The standard illustrated is made up of a tubular section 3 mounted on the base or frame and an adjustable section 4 telescoping 40 within the section 3 so that the height of the pedestal may be varied as desired within its scope of adjustment. The section 3 has a vertical slot 5 in one side thereof to receive the rack 6 on the section 4.

45 A driving worm 7 for the rack is provided, mounted in the ears 8 on the upright section 3 and provided with a shaft 9 having a handwheel 10 at its outer end. The worm 7 is provided as a means for driving the rack as it serves as a lock 50 for holding the adjustable section 4 of the pedestal in its adjusted position. However, to prevent accidental movement I provide a set screw 11 as a further means for locking the pedestal in its adjusted positions.

55 At its upper end the pedestal section 4 is pro-

vided with a supporting arm 12. This arm is in vertical alignment with and projects over the base. At the outer end of the arm I mount an adjusting bar 13 by means of the pivot 14 so that the adjusting bar can be swung in a vertical 60 plane on this pivot.

The adjusting screw and rest 15 is threaded through the arm to engage the under side of the bar. The adjusting bar is provided with a scale or gage 16 coacting with a pointer 17 on the 65 rear end of the arm 12 or otherwise suitably mounted on the adjustable member of the standard.

At the forward end of the bar 13 is a guide frame 18 which facilitates positioning of the device relative to the headlight to be tested as indicated at 19. At its rear end the bar 13 is provided with a handpiece 20 by means of which the machine may be manipulated to proper position relative to the headlight.

70 On the rear end of the bar I mount a housing 21 for the rearwardly inclined mirror or reflector 22, this reflector being preferably vertically curved. The housing is provided with a door or closure 23 which may be swung to the position shown by dotted lines in Figs. 4 and 5 to enclose and protect the reflector, or swung to open position when the apparatus is in use as shown by full lines in Figs. 4 and 5.

75 To prevent collapsing of the door against the rear side of the housing its upper edge is pivoted at 24 to hinged links 25, the hinged links 25 being pivoted to the housing at 26.

Between the door and the positioning frame I mount a U-shaped support 27 for the finder or 80 gage glass 28. This finder or gage glass is mounted in a rearwardly inclined position with its lower edge spaced from the bottom of the support so that rays from the lamp may pass below the gage glass, strike the reflector, and are reflected upon 85 the gage glass or finder. A forwardly inclined shield 29 extends upwardly from the lower edge of the finder so that the direct rays of a lamp cannot strike the finder.

90 A cover of black or other light excluding cloth 100 30 is hung over the reflector housing and finder support, the operator lifting the front end of this to inspect the reflection on the finder.

The finder is preferably provided with gaging or positioning indicia, a black horizontal line 105 across the glass as indicated at 31 being found quite effective for the purpose.

With the parts thus arranged the machine can be quickly positioned to headlights of various makes of automobiles now on the market and 110

adjusted to the position indicating the proper focusing of the lamp, that is, the distance from the vehicle at which it is desired the focusing point of the lamp shall strike the ground, and 5 the lamp then adjusted to the proper position.

I have not attempted to illustrate or describe certain other embodiments and adaptations of my invention which I contemplate as it is believed that this disclosure will enable those skilled 10 in the art to embody or adapt my improvements as may be desired.

Having thus described my invention what I claim as new and desire to secure by Letters Patent is:

- 15 1. In an apparatus of the class described, the combination of a vertically adjustable sectional standard provided with a supporting base, a forwardly projecting arm on the top section of said standard, a supporting bar pivotally mounted on 20 the front end of said arm for tilting adjustment in a vertical plane and provided with a positioning gage, said bar being provided with a hand-piece by means of which the device may be manipulated on its base, a screw for adjusting 25 and supporting said bar, a positioning frame at the front end of said bar adapted to facilitate positioning of the device relative to a headlight, a reflector housing at the rear end of said bar, a rearwardly inclined vertically curved reflector 30 mounted in said reflector housing, a U-shaped support mounted on said bar between said positioning frame and reflector, a translucent finder plate mounted on said support in a rearwardly inclined position and with its lower edge spaced 35 from the bottom of said support, a forwardly inclined shield extending upwardly from the lower edge of said finder plate, and a light excluding covering between the reflector housing and the finder plate.
- 40 2. A headlight tester provided with a supporting base, a standard carried by said base, a forwardly projecting arm on said standard, a supporting bar pivotally mounted on the front end of said arm for tilting adjustment in a vertical 45 plane, a positioning frame at the front end of said bar adapted to facilitate positioning of the device relative to a headlight, a reflector housing at the rear end of said bar, a rearwardly inclined vertically curved reflector mounted in said reflector housing, a U-shaped support mounted on 50 said bar between said positioning frame and reflector, a translucent finder plate mounted on said support in a rearwardly inclined position and with its lower edge spaced from the bottom of said support, a forwardly inclined shield extending upwardly from the lower edge of said finder plate, and a light excluding covering between the reflector housing 55 and the finder plate.

- 60 3. A headlight tester provided with a supporting base, a vertically adjustable sectional standard carried by said base, a forwardly projecting arm on the top section of said standard, a supporting bar pivotally mounted on the front end of said arm for tilting adjustment in a vertical 65 plane and provided with a positioning gage, said bar being provided with a handpiece by means of which the device may be manipulated on its base, a screw for adjusting and supporting said bar, a reflector housing at the rear end of said 70 bar, a rearwardly inclined curved reflector mounted in said reflector housing, a U-shaped support mounted on said bar in front of said reflector, a translucent finder plate mounted on said support in a rearwardly inclined position and with its 75 lower edge spaced from the bottom of said sup-

port, and a light excluding covering between the reflector housing and the finder plate.

4. A headlight tester provided with a supporting base, a standard on said base, a forwardly projecting arm on said standard, a supporting bar pivotally mounted on the front end of said arm for tilting adjustment in a vertical plane, a reflector housing at the rear end of said bar, a rearwardly inclined concave reflector mounted in said reflector housing, a U-shaped support mounted on said bar in front of said reflector, a translucent finder plate mounted on said support in a rearwardly inclined position and with its lower edge spaced from the bottom of said support, and a light excluding covering between the reflector housing and the finder plate.

5. A headlight tester provided with a vertically adjustable standard, a supporting bar mounted on the said standard for tilting adjustment in a vertical plane and provided with a positioning gage, a screw means for adjusting said bar, a positioning member at the front end of said bar adapted to facilitate positioning of the device relative to a headlight, a reflector housing at the rear end of said bar, a concave reflector mounted in said reflector housing, a U-shaped support mounted on said bar between said positioning member and reflector, a translucent finder plate mounted on said support with its lower edge spaced from the bottom of said support, a forwardly inclined shield 100 extending upwardly from the lower edge of said finder plate, and a light excluding covering between the reflector housing and the finder plate.

6. A headlight tester provided with a vertically adjustable standard, a supporting bar mounted on the said standard for tilting adjustment in a vertical plane and provided with a positioning gage, a positioning member at the front end of said bar adapted to facilitate positioning of the device relative to a headlight, a reflector housing 110 at the rear end of said bar, a concave reflector mounted in said reflector housing, a U-shaped support mounted on said bar between said positioning member and reflector, a translucent finder plate mounted on said support with its lower edge 120 spaced from the bottom of said support, a forwardly inclined shield extending upwardly from the lower edge of said finder plate, and a light excluding covering between the reflector housing and the finder plate.

7. A headlight tester provided with a vertically adjustable standard, a supporting bar mounted on said standard for tilting adjustment in a vertical plane and provided with a positioning gage, means for adjusting said bar, a reflector housing 130 at the rear end of said bar, an inclined curved reflector mounted in said reflector housing, a U-shaped support mounted on said bar in front of said reflector, a translucent finder plate mounted on said support with its lower edge spaced from the bottom of said support and positioned substantially at the focus of said curved reflector so that light reflected from a headlight by said reflector forms a line of light on said finder plate, and a light excluding covering between the reflector housing and the finder plate.

8. A headlight tester provided with a vertically adjustable standard, a support mounted on said standard for tilting adjustment in a vertical plane, a positioning gage operatively associated 145 with said support, a positioning member at the forward end of said support adapted to facilitate positioning of the device relative to a headlight, a concave reflector mounted on said support at an angle to the path of light from a headlight 150

- positioned relative to the positioning member and with its focus out of the path of light from the headlight, a finder plate mounted in front of and substantially at the focus of said reflector 5 so that light reflected from a headlight positioned relative to the positioning member is reflected as a line on said finder plate, and a light excluding covering between the reflector and finder plate, the finder plate being provided with a shield extending upwardly from its lower edge and on the side thereof opposite said reflector.
- 10 9. A headlight tester provided with a standard having a support mounted thereon for tilting adjustment in a vertical plane, a positioning member at the forward end of said support adapted to facilitate positioning the device relative to a headlight, a concave reflector mounted on said support and at an angle to the line of light from a headlight in position relative to said positioning member and with its focus out of the path of light from the headlight, and a finder plate mounted on said support in front of and substantially at the focus of said reflector and out of the line of light from a headlight positioned relative to said positioning means and directed at said reflector.
- 15 10. A headlight tester provided with a standard having a support mounted thereon for tilting adjustment in a vertical plane, a concave reflector mounted on said support and at an angle thereto and with its focus out of the path of light from the headlight, and a finder plate mounted on said support in front of and substantially at the focus of said reflector.
